UNITED STATES PATENT OFFICE

90,866

DESIGN FOR A CHAISE LONGUE

Conrad Bielecky, Elmhurst, N. Y., assignor to Bielecky Bros. Inc., New York, N. Y., a corporation of New York

Application March 24, 1933. Serial No. 47,578

Term of patent 7 years

To all whom it may concern:

Be it known that I, CONRAD BIELECKY, a citizen of the United States, residing at Elmhurst, county of Queens, and State of New York, have invented a new, original, and ornamental Design for a Chaise Longue of which the following is a specification, reference being had to the accompanying drawing forming a part thereof.

In the drawing:

Fig. 1 is a perspective view of my new and ornamental design for a chaise longue, including canopy or top.

Fig. 2 is a rear vertical plan view.

I claim:

The ornamental design for a chaise longue substantially as shown and described.

CONRAD BIELECKY.
